United States Patent Office

Des. 228,886
Patented Oct. 30, 1973

228,886

CONTAINER CLOSURE

Cecil Renou, Johannesburg, Transvaal, Republic of South Africa, assignor to Renou Plastics (Proprietary) Limited, Isando, Transvaal, Republic of South Africa

Filed Nov. 12, 1971, Ser. No. 198,503

Term of patent 14 years

Int. Cl. D9—99

U.S. Cl. D9—254

FIG. 1

FIG. 2

FIG. 3

FIG. 4

FIG. 1 is a top plan view of a container closure showing my new design;

FIG. 2 is a bottom plan view;

FIG. 3 is a front elevational view; and

FIG. 4 is a cross-sectional view on line 4—4 of FIG. 1.
I claim:

The ornamental design for a container closure, substantially as shown.
